CLAIM

The novel ornamental design for a transdermal delivery system frame, as shown and described.

DESCRIPTION

FIG. 1 is a front perspective view showing the frame according to the novel design;

FIG. 2 is a left side elevation view thereof;

FIG. 3 is a front elevation view thereof;

FIG. 4 is a right side elevation view thereof;

FIG. 5 is a rear elevation view thereof; and,

FIG. 6 is a bottom view thereof.

The broken lines are for illustrative purposes only and form no part of the claimed design.
